UNITED STATES PATENT OFFICE.

MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

EMBROIDERING ATTACHMENT FOR SEWING MACHINES.

Application filed April 10, 1920. Serial No. 372,759.

To all whom it may concern:

Be it known that I, MARTIN HEMLEB, a citizen of the United States, residing at Elizabeth, in the county of Union and State 5 of New Jersey, have invented certain new and useful Improvements in Embroidering Attachments for Sewing Machines, of which the following is a specification, reference being had therein to the accompanying drawings.

This invention relates to attachments for sewing machines and particularly to that class of attachments whereby a straight-away stitching machine may be easily converted into an embroidering machine.

This has heretofore been accomplished by rendering the feeding mechanism ineffective and manually shifting the work between successive stitches.

When machines are so operated it is desirable to replace the usual presser-foot with a special form of cloth-presser which acts merely as a needle stripper and bears lightly upon the fabric, adjacent the needle, only 20 while the needle is in the material to prevent the fabric from rising therewith and insure the throwing-out of the usual thread-loop which is seized by a suitable loop-taker.

The invention has for its object to provide 30 an improved form of a needle-stripper for this class of work which is simple and inexpensive in construction, effective in operation and which may be easily substituted for the usual presser-foot used for straight-away stitching.

The invention preferably comprises a needle-stripper having a shank slidingly held in a guide-way formed in the needle-clamp of the machine and a laterally projecting foot portion provided with a needle aperture. A spring acts upon the needle-stripper to yieldingly hold it depressed with 40 respect to the needle-clamp.

The improved form of needle-stripper 45 may be employed advantageously in connection with the feed cover-plate disclosed in U. S. Patent No. 937,112, dated Oct. 19, 1909 to Chas. Stafford and is so illustrated in the accompanying drawings in which Fig. 1 is a 50 perspective view of the attachment applied to the needle-bar of a sewing machine, together with the feed cover-plate above referred to. Fig. 2 is a central vertical sectional view of the parts shown in Fig. 1. Fig. 3 is a side elevation thereof with the

throat-plate and feed cover-plate in section and with the needle-bar in its lowermost position and the needle-stripper lifted by its contact with the fabric. Fig. 4 a rear side elevation of the improved needle-stripper 60 and Fig. 5 is a sectional view taken on the line 5—5 of Fig. 3.

Referring more particularly to the drawings the improved needle-stripper is shown sustained by the needle-bar 1 provided with 65 a groove 2 for the reception of the needle 3 which cooperates with a suitable loop-taker (not shown) located beneath the throat-plate 4 which is provided with feed slots 5 and a needle-hole 6. A feed cover-plate 7 is 70 supported by the throat-plate 4 and acts to render ineffective a suitable feed-dog (not shown) which normally operates through the feed slots 5. A needle-clamp 8, in the form of a sleeve, is fitted about the lower 75 end of the needle-bar and is formed with a boss 9 through which is threaded a clamp screw 10 having its inner end contacting with the needle-bar 1 thereby securing the needle clamp to the needle-bar 1 and the 80 needle 3 in the groove 2.

The improved needle-stripper comprises 85 preferably a shank portion 11 and a laterally projecting foot portion 12 provided with a needle aperture 13. This shank 11 is 90 slidingly mounted in a guide-way 14 formed in guide-block 14' fixedly secured to the needle-clamp 8, and is provided with an aperture 15 affording clearance for the boss 9 which projects through the shank 11 and 95 guideway 14. A spring 16 acts to yieldingly hold the needle-stripper depressed with respect to the needle-clamp and is provided with one arm 17, which is connected to the guide-block 14' and another arm 18 connected at 19 to the shank 11.

Inasmuch as the needle-stripper is slidingly secured to the needle-clamping sleeve independently of the clamp-screw, it is obvious that the screw may be loosened for the 100 purpose of replacing the needle without disturbing the operative relation between the clamping sleeve and the needle-stripper.

During the formation of an embroidery 105 stitch the needle-stripper descends in unison with the needle until the foot-portion contacts with the fabric *f*, then a continued downward movement of the needle-bar compresses the spring 16 and slides the shank upwardly in the guideway 14 until the 110

needle-bar reaches the limit of its downward movement as shown in Fig. 3. From this position the needle moves upwardly and throws out the thread-loop which is seized 5 by the loop-taker. During the initial upward movement of the needle the foot 12 bears upon the fabric under the action of the spring 16 and prevents the fabric from clinging to and rising with the needle and 10 thus preventing complete formation of the loop. After the needle thread-loop has been seized by the loop-taker the boss 9 comes in contact with the upper wall of the aperture 15 and causes the foot to rise thereafter in 15 unison with the needle.

Having thus set forth the nature of the invention what I claim herein is:

1. An embroidering attachment including, in combination, a needle-clamp provided 20 with a lateral boss, a guide-block secured to said needle-clamp and formed with a guideway, a needle-stripper provided with a slotted shank entered by the needle-clamp boss and slidably mounted in said guideway and a spring acting upon the needle-stripper to yieldingly hold it depressed with respect to the needle-clamp.
2. In an embroidering attachment for 30 sewing machines having a needle-bar provided with an external groove for receiving a needle, in combination, a needle-clamping sleeve surrounding said needle-bar, a needle-stripper slidably mounted thereon and supported solely by said needle-clamping sleeve, 35 a spring for said needle-stripper, and means carried by said sleeve for securing it to said needle-bar and for causing said sleeve to clamp said needle in said groove.
3. In an embroidering attachment for 40 sewing machines provided with a needle-bar having a groove for the reception of a needle,

in combination, a needle-clamp secured to said needle-bar, a guide-block supported by said needle-clamp, and formed with a guideway, a needle-stripper slidably mounted in said guideway, a spring having an arm connected to said guide-block and another arm connected to said needle-stripper for holding the latter depressed in said guideway and a clamp-screw threaded through said needle-clamp and contacting with the needle-bar for securing said needle-clamp and needle-stripper to the needle-bar and for causing said sleeve to clamp a needle in the groove in said needle bar.

4. In an embroidering attachment for sewing machines having a needle-bar provided with an external groove for receiving a needle, in combination, a needle-clamping sleeve surrounding said needle-bar, a clamp-screw threaded through said needle-clamping sleeve and contacting with said needle-bar for securing said needle-clamping sleeve to said needle-bar and causing said sleeve to clamp a needle in said groove, and a spring-pressed needle-stripper slidably mounted on said needle-clamping sleeve and supported solely thereby and independently of said clamp-screw.

5. An embroidering attachment including in combination, a needle-clamp having a lateral boss, a guide-block secured to said clamp and formed with a guideway, a needle stripper slidably mounted in said guideway in engagement with said boss by which it is maintained in the guideway, and a spring for yieldingly holding said stripper depressed relatively to the needle-clamp.

In testimony whereof, I have signed my name to this specification.

MARTIN HEMLEB.
